**FIRE DETECTOR CIRCUIT ARRANGED TO
PREVENT FALSE WARNING**

John E. Lindberg, 3296 Springhill Road, Lafayette, Calif.
Filed May 21, 1962, Ser. No. 196,303
5 Claims. (Cl. 340—214)

This invention relates to improvements in warning or alarm circuits, especially to those used for the detection of fires in airplanes and elsewhere.

Fire-detection circuits and some other types of warning circuits heretofore in use have been prone to give false alarms. Recent statistics indicate, for example, that on the commercial airlines in the United States alone there are, on the average, two false fire warnings per day. During one period of time for one type of aircraft, there were no more than two engine fires reported (and one of them not confirmed) while thirty-seven engines were reported shut down in flight and eighty-five ground delays or interruptions were reported, all due to false fire warnings. Each false warning in flight is liable to cause a fatal crash, and several of these have occurred each year in recent years. Even when the plane and passengers are saved, each false fire warning in flight requires immediate remedial action, such as dumping excess fuel down to the allowable landing weight and landing as soon as possible. The resultant disruption of the schedule, the cost of landing, taking off again, and obtaining clearances, and other expenses resulting from this false warning have been estimated to add more than \$20,000 on the average per false fire warning on large commercial planes.

An important object of the invention is to provide a fire detection circuit far less liable to give false fire warnings than those heretofore in use.

An important cause of false warnings in fire-detection systems has been short circuits in the electrical portion of the fire detector, and it is an object of this invention to prevent such short circuits, so that they become next to impossible.

Many current fire detectors give false warnings when a portion of the circuit is grounded, and another object of the invention is to provide a fire-detection circuit that will almost never give false warnings even when the circuit is grounded.

Other objects of the invention will appear from the following description of some preferred embodiments.

In the drawings:

FIG. 1 is a fire detection circuit diagram embodying the principles of the invention. The fire detector sensor is broken in order to conserve space.

FIG. 2 is a view in elevation and in section of a portion of a fire detection unit embodying a modified form of the invention.

FIG. 3 is a circuit diagram of another modified form of the invention, in which a battery is rechargeable.

FIG. 4 is a circuit diagram of still another modified form of the invention in which the battery of FIG. 2 is rechargeable.

FIG. 5 is a circuit diagram of a modified form of the invention generally like FIG. 1 showing the use of alternating current.

A key point of some forms of this invention is the use of a battery as the power source and, more important, its location closely adjacent the fire detector responder. FIG. 1 shows a circuit using a fire detector sensor 10 and responder 11 like those described in application Serial No. 815,406 filed May 25, 1959, now Patent No. 3,122,728, issued February 25, 1964. For those unacquainted with that application, it may be said that the sensor 10 contains a gas or a gas-emitting material that when heated increases the pressure inside the sensor and transmits that pressure

2

to the responder 11, a pressure-actuated switch that, when actuated, closes the otherwise open circuit. The sensor 10 of Serial No. 815,406 is not electric in its function, and therefore the actuation under operational conditions of the responder 11 does not depend on any electric circuit. Actuation of the responder is indicated by a warning device 12, comprising, for example, two lamps 13 and 14 and a horn 15 in parallel.

A key feature of this invention is the location of a battery 16, as a power supply between the responder 11 and the warning device 12, and, in fact, the closer to the responder 11 the better. In FIG. 1, there is a very short line 17 connecting the battery 16 to the responder 11, and a much longer line 18 connecting the battery 16 to the warning device 12. Return lines 19 and 20 connect the warning device 12 to the responder 11.

For test purposes, a switch 21 and line 22 connect a larger test battery 23 to the sensor 10, returning through the line 20, heating the sensor 10 and actuating the responder 11 when the testing switch 21 is closed. For normal use, the test circuit may be disregarded, for it is not a cause of false warning, cannot itself actuate the warning device 12, and operates only when the switch 21 is closed.

The key feature of locating the battery 16 for the warning circuit close to the responder 11 is quite important, for no combination of grounds, short circuits, or wiring failures which does not include the short lead 17 can give a false warning, for unless the line 17 is shorted to the other side of the battery 16, the battery cannot cause the lamps 13 or 14 to light or the horn 15 to sound. This happens when the responder 11 is actuated but not otherwise. Thus, if any of lines 18, 19, or 20 is grounded, or if all of lines 18, 19, and 20 are grounded or short circuited to each other, there will still be no false warning so long as the short line 17 is not grounded or connected to one of the lines 19 or 20. Of course, the line 17 can even be grounded without producing a false warning so long as no other line is grounded, but since the line 17 is short, special care is easily taken to prevent its grounding.

A special instance of such care is shown in FIG. 2. Here, the responder 11 is surrounded by a housing 25. At the lower end a snap ring 26 holds in a flanged tubular insulator 27, and an insulator disc 28 retains an insulating sleeve 30 inside the upper portion of the housing 25 above the responder 11. A battery 16, preferably of the nickel-cadmium type, is located directly on top of a responder housing member 31 with the conductor 17 wholly inside the housing 31. The battery 16 has a terminal 32, against which a contact member 33 is held by a spring 34 that engages the disc 28. The member 33 has a stud 35 that extends outside the disc 28, and the wire 18 is connected to it, as by a plug threaded onto the housing 25. The battery 16 can even be inside the responder housing 36, by forming the housing 36 larger in order to include it. The length of the lead 17 is about the minimum and is also almost fully protected from grounding.

Provided that the battery 16 is of rechargeable type, such as a rechargeable nickel-cadmium cell or a wet cell, it may be recharged as shown in FIG. 3. Here a source of power 40, such as a generator, is connected to ground through an upper resistor 41 of a suitable high value, a central resistor 42 adapted to a potential drop corresponding to the voltage of the battery, and a lower resistor 43 of high value. Thus, for a 28-volt power source 40, the resistors 41 and 43 may each be 500,000 ohms, and the resistor 42 may have a value of 10,000 ohms. The resistor 42 is connected across the battery 16 by leads 44 and 45. The battery 16 operates when the generator 40 is not used and is recharged when the generator 40

is used. Preferably, one of the leads 44, 45 contains a blocking rectifier 44a to prevent discharge of the battery 16 when the power source 40 is discharged or disconnected.

When the battery 16 is inside the responder 11, as in FIG. 4, it may still be recharged at testing time, by connecting a charging supply 46 to the line 19 by a line 47 and to a switch contact 48 by a line 49. The line 19 is thus divided into segments 50, 51 and 52. When a switch 53 is connected to a terminal 54, all three segments 10 50, 51 and 52 are in the circuit with the battery 16, depending on actuation of the responder. A test switch 55 connects a test source of power 56 into a circuit of the sensor, the line 22 and the segment 20. When the switch 55 is thrown to "test," the power source 56 heats the 15 sensor 10 and causes the responder 11 to close the circuit. Then the switch 53 can be thrown and the charging supply 46 supplies current that acts to charge the battery during testing. By separate operation of the switch 55 when the switch 53 is in its normal, non-charging position, the operability of the battery 16 can be tested.

FIG. 5 shows a circuit generally like that of FIG. 1, with the same numbers generally used, except that a transformer 60 is used in place of the battery 16. This, of course, has some disadvantages, in that the location 25 of the transformer 60 causes problems as compared with batteries, but it will be noted that grounding of the transformer primary 61 or of its leads, does not effect actuation of the signal means 12, and, of course, again, grounding of the lines 19 and 20 does not actuate the 30 signal means 12. Therefore, again the likelihood of a false fire warning is reduced.

To those skilled in the art to which this invention relates, many changes in construction and widely differing embodiments and applications of the invention will suggest themselves without departing from the spirit and scope of the invention. The disclosures and the description herein are purely illustrative and are not intended to be in any sense limiting.

I claim:

1. A critical-temperature-detection system comprising an imperforate electrically conductive enclosure of extended length;

heat-to-pressure transducing means for substantially increasing the pressure within said enclosure when said enclosure is externally heated;

pressure-actuated switch means actuated by the pressure in said enclosure;

an electrical warning circuit including, in series, signal means, a first source of electrical current, said switch means, and a return line from said switch means to said signal means, so that when said first switch means is closed by a pressure increase in said enclosure it causes said warning circuit to actuate said signal means; and

a test circuit including, in series, a second source of electrical current, an external switch, said conductive enclosure, and said return line to said second source so that said transducing means can be electrically heated to cause closure of said pressure-actuated switch means and therefore actuation of said signal means,

said return line being connected to both said conductive enclosure and to one side of said pressure-actuated switch means, and said first source being located between the other side of said pressure-actuated switch means and said signal means,

so that grounding of said enclosure or said return line cannot result in a false warning by actuation of said signal means, whereas actual closing of said pressure-actuated switch means does result in actuation of said signal means.

2. The system of claim 1 wherein said first source of

electrical current comprises a battery located physically closely adjacent said switch means.

3. The system of claim 1 wherein said first source of electrical current comprises a transformer.

4. A critical-temperature-detection system comprising an imperforate electrically conductive enclosure of extended length;

heat-to-pressure transducing means for substantially increasing the pressure within said enclosure when said enclosure is externally heated;

a housing having a first end connected to said enclosure and a second end;

pressure-actuated switch means in said housing actuated by the pressure in said enclosure and having a first side connected to said enclosure and a second side;

a source of electrical current connected to said second side of said switch means and physically located closely adjacent said second end of said housing; signal means connected to said second side of said switch means through said source;

and return means from said first side of said switch means and said enclosure to said source signal means so that when said switch means is closed by a pressure increase in said enclosure it causes said circuit to actuate said signal means and

so that grounding of said enclosure and said return means does not cause actuation of said signal means; and

a test circuit including means for sending current through said enclosure and at least part of said return means for electrically heating said transducing means and thereby causing closure of said switch means and therefore actuation of said signal means.

5. A critical-temperature detection system for use where there is a detection zone in one location and a signal zone in a different location distant from the detection zone, comprising:

indicator means at said signal zone,

a housing at said detection zone, having a switch chamber,

a battery inside said housing and insulated therefrom, electrical conduit means external of said housing, said conduit means connecting said indicator means to one terminal of said battery,

pressure-actuated switch means inside said chamber and including a stationary electrode and a movable switch member, said stationary electrode being in direct contact with a second terminal of said battery, an imperforate stationary enclosure of extended length in said detection zone, connected to said chamber and otherwise external of said housing,

heat-to-pressure transducing means in said enclosure for substantially increasing the pressure within said enclosure when said enclosure is externally heated, return electrical conduit means external of said housing and connecting said indicator means to said movable switch member so that said movable switch member is operated by a pressure increase in said enclosure moving said movable switch member against said stationary electrode, said battery then actuating said indicator means,

the direct engagement of said battery by said stationary electrode inside said housing preventing false alarms, since said indicator means cannot be actuated by grounding of either or both of said conduit means.
